COOKING UTENSIL COVER KNOB

Robert A. Eckersberg and James L. Hvale, Chicago, Ill.,
assignors to Ekco Products Company, Chicago, Ill., a
corporation of Illinois

Application December 16, 1959, Serial No. 58,682

Term of patent 14 years

(Cl. D44—29)

Fig. 1 is a top plan view of a cooking utensil cover knob embodying the present design.

Fig. 2 is a side elevational view thereof.

Fig. 3 is a similar view showing the article as it appears when rotated through an angle of 90 degrees about an upright axis relative to position shown in Fig. 2.

Fig. 4 is a sectional view taken along line 4—4 of Fig. 1.

We claim:

The ornamental design for a cooking utensil cover knob, as shown.
